A. Hall.

Piano.

No. 10450.

Patented Jan 24, 1854.

UNITED STATES PATENT OFFICE.

ALEXANDER HALL, OF LLOYDSVILLE, OHIO.

PIANOFORTE.

Specification of Letters Patent No. 10,456, dated January 24, 1854.

To all whom it may concern:

Be it known that I, ALEXANDER HALL, of Lloydsburg, in the county of Belmont and State of Ohio, have invented certain new 5 and useful Improvements in Pianofortes, and that the following is a full, clear, and exact description of the principle or character which distinguishes them from all other things before known and of the usual 10 manner of making, modifying, and using the same, reference being had to the accompanying drawings.

My invention and improvement consists in a new mode of playing the piano in octaves 15 accompaniments, by one and the same key, and in playing one or more octaves at one and the same time at pleasure. And also in combination with my mode of accomplishing this desirable object, I have invented 20 a new arrangement of dampers by which I can at pleasure introduce the octave notes, omit them, or use them separately. I am aware that great and various efforts have been made to introduce the octaves 25 upon the piano beyond the reaching power of the fingers, and from the great brilliancy of effect produced by such a performance, it has become such a desideratum that great artists have even resorted to extra or artistic 30 fingers attached to and controlled by the movements of the hand for this purpose. Notwithstanding, however the importance of the subject, I believe that at present, no such pianos are in use, in consequence of the 35 great complication of the instrument introduced by devices to accomplish this purpose, and also from the greater hardness or heaviness of the touch. By my improvement I have attained the most extensive capabilities 40 for the piano forte with very great simplicity.

Figure 1 is a plan of the instrument giving a top view of the strings, bridges, and dampers, with their attachments to the 45 frame and the position of the hammer heads. Fig. 2 is an elevation in perspective of the same. Fig. 3 is a transverse section of one of the extra bridges.

Similar letters refer to similar parts in 50 the different figures.

My modes of accomplishing the said improvements are illustrated as follows. In order to obtain the octave notes, I employ two or more extra bridges, B, C, arranged 55 upon the sounding board—in front of the bridge at present in use—upon which the

respective strings to produce the octave notes have their bearings. These bridges are arranged a suitable distance apart, and are provided with notches or depressions, a^1 , a^1 , 60 etc., over which pass the leading strings, or the ordinary strings for piano fortés; and the bearings b^1 , b^1 , on these bridges are for the octave strings. Thus there are four strings to each set, or each hammer, as 65 shown in the drawings, two leading strings and two octave strings. The number of octave or leading strings may be varied at pleasure. The strings bearing upon the bridge B, are tuned an octave above the 70 leading strings, and those bearing upon the bridge C, are tuned an octave above those bearing on bridge B, for each set.

The leading strings are represented by s^1 , s^1 , and the first and second octaves for the 75 same set by S^8 , and S^{15} respectively. The arrangement of these octave strings, one on each side of the leading strings, gives room and facility for damping the octaves one or both at pleasure, by the contrivance next to be described. Two damper bars, e , d , are connected with the frame work of the instrument by means of the levers h , h , jointed or pivoted at i , i . These dampers extend across the piano and are for the purpose of 80 damping the octaves at pleasure. Damper e , is for the set of the first octave strings, S^{15} , and damper d , is for the second octave strings S^8 .

By my arrangement of the strings and dampers, it will be seen that the first octaves for different sets of strings coming into proximity, may be reached by the dampers f , f , in the most simple and convenient manner—and the same is true of 95 the second octave strings s^8 , and dampers g , g , these two octave strings to each set, being alternately changed to the right and left of the leading strings for that purpose, as will be seen by the drawings. The hammer heads, c^1 , c^1 , strike all four of the strings in the set, but those which are damped do not sound. It may be remarked here, that the position of the dampers may be reversed, and they may be made to bear 100 upward from below the strings instead of above as at present. This will of course be understood by any piano forte maker.

In forte passages the damper belonging to the strings s^8 s^8 , can be raised, together with the usual dampers of the piano forte, and in fortissimo passages, all the dampers can 110

be raised at once, and thus produce a splendid and uncommon effect. But the great beauty of this improvement is to be found in its rich variety of combination. The 5 performer can play upon the leading strings as usual, or upon the leading strings and the first octave, or upon the leading strings and the second octave, or upon all three combined, and a performance thus achieved 10 which will equal in effect that of three performers at once. The strings are attached to the tuning pins, in the tuning block D, and to pins at the other end of the frame of the piano, and pass over and rest upon the 15 bearing plate b, and bridge A, after the manner of common pianos.

The hammers c^1 , c^1 , are of common construction and operation, and so also are the 20 pedal rods c^2 , c^2 , well as all other parts of the piano forte not described.

I do not claim the employment of extra strings or extra bridge or bridges for the introduction of the lower octave notes as they are set forth in the patent of Simeon 25 Draper granted June 20th 1845, in which an extra bridge is used outside the regular

bridge thereby elongating the instrument, but I shall confine my claim to the upper octave strings, and bridges therefor, placed within the usual bridges of the piano forte. 30

Therefore what I claim as my invention and desire to secure by Letters Patent are—

1. The mode substantially as herein described, of introducing upper octave notes in piano fortés, said mode consisting essentially in the employment of extra strings and extra bridges, as set forth, so that the performer can play in one or more octaves at the same time with the same facility as he could execute ordinary music on the 40 common piano.

2. I claim the arrangement of the dampers for the octaves, in combination with the alternate changes of the two upper octave strings to the right and left of the leading 45 strings in each set, for the purposes and substantially in the manner set forth.

ALEX. HALL.
